TRAIN CONTROL

Filed Nov. 17, 1924

FIG. 1.

FIG. 2.

H. B. Taylor, INVENTOR.
BY Neil C. Preston,
his ATTORNEY

UNITED STATES PATENT OFFICE.

HERBERT B. TAYLOR, OF ROCHESTER, NEW YORK, ASSIGNOR TO GENERAL RAILWAY SIGNAL COMPANY, OF ROCHESTER, NEW YORK.

TRAIN CONTROL.

Application filed November 17, 1924. Serial No. 750,309.

This invention relates to automatic train control systems and more particularly to a means for automatically detecting a failure of the driving mechanism for the car-carried apparatus connected to the car wheels.

In the type of train control system commonly known as a train speed control system, the car-carried equipment includes some suitable type of speed responsive device, usually a centrifuge, driven in accordance with the actual speed of the vehicle, by means of which a restrictive control is imposed when the vehicle speed has increased above a safe value under the existing traffic conditions in a given section of the trackway. It is obvious that if for any reason the driving mechanism for this speed responsive device becomes broken or disconnected, the device will indicate a zero speed, and the car-carried equipment will not set up the desired speed restriction.

With the above and other considerations in mind it is proposed in accordance with the present invention to provide means for checking the operation of the driving mechanism for the car-carried speed responsive device, and for initiating an automatic restrictive control if this device fails to operate while the train is in motion; and more specifically, it is proposed to provide apparatus for imposing an automatic brake application on the vehicle if the car-carried speed responsive device fails to indicate a given speed after steam has been impressed on the locomotive cylinders for a limited period of time.

Other objects, characteristics, and advantageous features of the present invention will become apparent as the description thereof progresses.

In the drawings, Fig. 1 represents the checking device comprising the present invention, together with a diagrammatic representation of the trackway and car-carried apparatus of a simplified automatic train control system of the train speed control type; and

Fig. 2 is a partial view of a modified form of the checking device shown in Fig. 1.

It is understood that the checking apparatus for the speed responsive device comprising the present invention might be used in connection with any suitable form of automatic train control system of the speed control type, but for the purpose of illustra-

tion, an extremely simple form of train speed control system employing the well known continuous inductive method of influence communication has been shown. Before describing the check for the drive of 60 the speed responsive device, a brief description of the simplified train control system shown will be given.

Referring to Fig. 1, the track rails 1 have been shown divided into the usual blocks by 65 the insulating joints 2, the block I and the ends of two adjacent blocks H and J having been shown. The usual track relays 3 are connected across the track rails 1 at the entrance ends of the blocks, these relays being energized by the track batteries 4 which are connected across the track rails at the exit ends of the blocks; the normal direction of traffic being indicated by the arrow. The track relays 3 operate the movable contact 70 fingers 5 and 6 which control a circuit for impressing an alternating control current across the track rails at the entrance ends of each block from the transmission line 7, this circuit including the transformers 8 and 9 as clearly shown.

The usual wayside signals Z of the semaphore type have been shown in a conventional manner at the entrance of each block, it being understood that any other suitable 85 type of wayside signals might be employed, or the system may be used without wayside signals.

It is obvious that, if a train is located in a given block, its wheels and axles will 90 shunt the track battery 4 and the secondary winding of the transformer 9, causing the track relay 3 to be de-energized and the control current to be cut off or substantially reduced in the track rails behind the train. 95 The de-energization of the track relay of each block will cause the control current to be cut off from the track rails in the block next in the rear by the retraction of the contact fingers 5 and 6 of this relay.

A railway vehicle is conventionally represented in the block H by the wheels and axles 10, this vehicle being provided with the usual inductive receiving coils 11 mounted in inductive relation to the track rails 1, in 105 front of the leading axle of the vehicle. These receiving coils 11 are connected to the input circuit of a suitable amplifier, preferably of the audion or vacuum tube type, which has been conventionally represented 110

at A, the output circuit of this amplifier being connected to the main relay MR as shown. This relay MR may be a single element alternating current relay, of the vane or rotor type operated split phase, or by using a rectifying tube or tubes, this relay may be a direct current relay of the tractive type. This main relay MR is provided with a movable contact finger 12 and a stationary front contact 13, which contacts are included in a control circuit as hereinafter described.

A speed responsive device is provided for indicating or determining the vehicle speed, and may take any suitable form; but for the purpose of illustrating the invention, a simple centrifuge G has been shown. This centrifuge G comprises a shaft 14 geared or otherwise suitably driven from an axle of the vehicle, and carrying a fixed collar 15 and a movable collar 16, these collars being connected by the links 17 carrying the weights 18, and being urged apart by the spring 19. It is evident that as the vehicle speed increases, the weights 18 will be thrown outwardly by centrifugal force drawing the movable collar 16 downwardly against the pressure of the spring 19. A pivotally supported speed arm 20 engages a groove in the movable collar 16, and is arranged to be moved over the contact segments 21, 22 and 23 and 24 in accordance with the vehicle speed as indicated by the centrifuge G. These contact segments act to make and break various control circuits at different speeds as hereinafter described.

The automatic control of the brakes of the vehicle may be effected in any suitable manner and by means of any suitable automatic brake control devices. As the automatic initiation of a brake application is usually effected by means of some suitable air valve, an electro-pneumatic valve EPV has been shown in the drawings, it being assumed that this electro-pneumatic valve acts in some suitable manner to initiate a brake application upon the de-energization of a circuit through its windings.

Referring now more particularly to the apparatus comprising the present invention the means for checking the operation of the speed responsive device includes a combined steam and air operated circuit controlling device D. This device D comprises a steam chamber 25, which is closed at one end by a flexible diaphragm 26, and which is connected by a suitable pipe 27 to the steam header or pipe between the throttle valve and the locomotive cylinders. The diaphragm 26 operates a valve 28 against the pressure of a spring 29, this valve 28 acting to vent the air chamber 30 to atmosphere through the ports 31 and 32 when steam pressure is supplied to the chamber 25, at the same time closing the air supply pipe 33. The air chamber

30 is provided with a flexible diaphragm 34 which is connected to a movable contact member 35 and is biased by the spring 36. The air supply pipe 33 is connected to the main reservoir of the train air brake system or other suitable source; and hence, when no steam pressure is supplied to the chamber 25 and the port 31 is closed by the valve 28, main reservoir pressure will be supplied to the air chamber 30, causing the diaphragm 34 to move to the left against the pressure of the spring 36, thereby bringing the contact member 35 into a position to engage its associated stationary contacts 37 and 38. When the air chamber 30 is vented to atmosphere, the contact member 35 will be moved by the spring 36 to disengage the fingers 37 and 38.

In the modification of the invention shown in Fig. 2, the air supplying pipe 33 is provided with a check valve 44, the remainder of the apparatus being identical with that shown in Fig. 1. The check valve may be of any suitable type, and is shown in a simplified form, the operation of which will be readily apparent from the drawings. In this form of the invention, the pipe 45 leading through the check valve 44 to the air pipe 33, is connected to the "brake cylinder pipe" of the well known ET equipment, or other suitable connections are made so that air pressure is admitted to the pipe 45 only when the brakes are being applied on the engine and tender. The check valve 44 is arranged to admit air pressure to the pipe 33 when these brakes are applied, and to prevent the air thus admitted from being exhausted through the pipe 45 when the brakes are released.

Operation.—All of the apparatus in the drawings has been shown in its normal operating condition, that is, the positions of the various devices are such as would be assumed with a train running at a speed below the maximum but above the minimum permissive limit, under clear traffic conditions ahead, and with the locomotive throttle valve open. The letters B and C have been used to indicate the opposite poles of a suitable source of energy, preferably a storage battery.

Referring briefly to the operation of the simplified train control system shown, assuming a train to be proceeding under clear traffic conditions, that is, with no other train in the block in which it is located or in the next block in advance, train control current flows in the track rails and induces currents in the receiving coils 11; and these currents are amplified by the amplifier A and cause energization of the main relay MR, attracting its contact finger 12 and closing its front contact 13. An energizing circuit for the electro-pneumatic valve EPV is now completed, which circuit may be traced as follows:—from the battery terminal B, contact finger 12 and the front contact 13 of the main relay MR, wire 39, contact segment 23, speed

arm 20 to contact segment 24, and wires 40 and 41 through the winding of the electro-pneumatic valve EPV to the battery terminal C. With the electro-pneumatic valve EPV energized, the train may proceed in the clear territory under the sole restriction indicated below.

The contact segment 23 is preferably constructed to impose a maximum speed limit under clear traffic conditions, that is, when the train speed exceeds a given maximum speed, say 60 miles per hour, the speed arm 20 will disengage the contact segment 23 and the energizing circuit for the electro-pneumatic valve traced above, will be broken, causing a de-energization of this valve and a consequent automatic brake application which continues until the train speed has been brought below the maximum limit, when the speed arm 20 again engages the segment 23 and the energizing circuit for the electro-pneumatic valve is again completed.

When a train equipped with the system shown enters a block in which caution or danger traffic conditions exist, that is, a block in which another train is located or the first block in the rear of such occupied block, the train control current is cut off from the track rails and the receiving coils 11 do not have current induced therein, which condition results in the de-energization of the main relay MR and the consequent retraction of its contact finger 12. When the contacts 12 and 13 of the main relay MR are open, the energizing circuit for the electro-pneumatic valve EPV traced above is broken, and an automatic brake application results. This automatic brake application continues until the train speed has been reduced to a minimum value, assumed to be 15 miles per hour, at which speed the arm 20 engages the contact segment 22, completing an energizing circuit for the electro-pneumatic valve which may be traced as follows:—from the battery terminal B, through contact segment 22 and speed arm 20, contact segment 24, wires 40 and 41 and the winding of the electro-pneumatic valve EPV to the battery terminal C. The train may now proceed in the caution or danger territory at a speed below the minimum limit, and is held to that speed until traffic conditions ahead become more favorable.

Referring now more particularly to the operation of the check for the drive of the car-carried speed responsive apparatus which comprises the present invention, assume that a train is proceeding under clear traffic conditions with the throttle valve open, and that the drive mechanism becomes broken or disengaged for some reason. Under these conditions the centrifuge G stops rotating and the speed arm 20 will assume its zero speed position. In this position, the contact segment 24 does not engage the arm 20 as this

segment is arranged to disengage the arm when zero speed is indicated. As the throttle valve is open, the circuit controlling device is in the condition shown, that is, the steam chamber 25 is supplied with pressure, actuating the valve 28 and so venting the air chamber 30 to atmosphere and causing the movable contact 35 to disengage its associated stationary contacts 37 and 38. The energizing circuit for the electro-pneumatic valve EPV will be broken when the speed arm 20 disengages the contact segment 24, causing an automatic brake application and bringing the train to a stop. The engineer now may repair the driving mechanism or, preferably, render the automatic brake control apparatus inactive by the operation of a suitable cut-out device, not shown, which is provided in connection with the automatic train control system, this cut-out device being protected against unauthorized operation to avoid an automatic brake application by means of a sealed casing or other suitable means.

If the steam is cut off at the time at which the drive mechanism becomes disengaged, the valve 28 of the circuit controlling device D will close the port 31 and open the pipe 33 which is connected to the main reservoir air pressure, causing the diaphragm 34 to be moved to the right and thus causing the contact member 35 to engage its associated contacts 37 and 38. A circuit to the electro-pneumatic valve EPV will now be completed which circuit may be traced as follows:—from the battery terminal B, contact segment 22 through the speed arm 20 to the contact segment 21 which engages the arm 20 at speeds below 3 miles per hour, wire 42, contact finger 37, contact member 35 and contact finger 38 of the circuit controlling device D, wires 43 and 41, and the winding of the electro-pneumatic valve EPV to the battery terminal C. With the electro-pneumatic valve energized, the train may proceed without restriction so long as the throttle is closed, and no steam pressure is applied to the chamber 25, but as soon as the throttle is opened the contacts 35, 37 and 38 will be opened in the manner described above, and the electro-pneumatic valve will be de-energized, causing an automatic brake application and bringing the train to a stop.

The spring 29 of the circuit controlling device D operates to move the valve 28 into a position to open the air pipe 33 and to close the port 31 when no steam pressure is present in the chamber 25. This spring 29 also serves another function, namely, to prevent a slight steam pressure arising from a leaking throttle valve from moving the valve 28 when the train is not in motion.

It should be noted that if the train is proceeding under caution or danger traffic conditions at the time at which the drive mecha-

nism becomes disengaged or inoperative, the 5 operation of the device D and its associated circuits is the same as that described in connection with a failure of the drive under clear traffic conditions, the circuit to the electro-pneumatic valve EPV through the contacts 37, 35, and 38 of the device D being completed through the contact segment 22 which is connected to the battery terminal B, the arm 20, 10 and the segment 21.

Now assume that the train under consideration comes to a stop under either clear, caution or danger traffic conditions. As the train approaches a zero speed, the throttle will be 15 closed and hence the contacts 37 and 38 are closed by the contact member 35 in the manner described above, thus completing a circuit to the electro-pneumatic valve EPV through the contact segments 22 and 21, which circuit has 20 been traced above. When the train starts, the throttle is, of course, opened, closing the pipe 33 and venting the air chamber 30 to atmosphere through the ports 31 and 32. The volume of the chamber 30 and the size of the 25 ports 31 and 32 are so constructed and arranged that a certain time will elapse before the spring 36 moves the contact member 35 out of engagement with its associated contacts 37 and 38, this time being long enough 30 to allow the train to get in motion and so to bring the speed arm 20 into engagement with the contact segment 24, thereby completing a circuit to the electro-pneumatic valve EPV through the contact segment 22, which circuit 35 has been traced above.

It is evident from the discussion given above that when the centrifuge G is in its zero speed position due to a lack of motion of the train, an automatic brake application will 40 not result.

If a train equipped with the apparatus shown in Fig. 1 is proceeding at a high rate of speed and with the throttle valve closed, and if the drive mechanism becomes disengaged 45 under these conditions, it is obvious that the train might proceed into a caution or a danger block without restriction particularly if it is traveling on a down grade. In the modification shown in Fig. 2, this possible danger is 50 avoided by supplying the air pressure for the pipe 33 from the "brake cylinder pipe" of the well known E. T. equipment through a check valve as described above. With this arrangement, pressure will not be supplied to the air 55 chamber 30 unless the brakes are being applied on the locomotive, and hence the contacts 37, 35 and 38 cannot be closed to energize the electro-pneumatic valve EPV unless a 60 brake application is being made.

In a system embodying the modification 65 shown in Fig. 2, when an automatic brake application occurs as a result of a failure of the governor drive shaft, air pressure is supplied from the brake cylinder pipe through the pipe 45, the check valve 44 and the pipe

33 to the chamber 30, and, if the throttle is still closed, the chamber 30 is charged and the contacts 37, 35 and 38 are closed. This causes the energization of the electro-pneumatic valve EPV and permits release of the 70 brakes as described above, and when the brakes are released, the air pressure in the chamber 30 is trapped by the check valve 44, thus maintaining the contacts 37, 35 and 38 closed. After a time, the pressure trapped in 75 the chamber 30 leaks away through the valves 44 and 28, the contacts 37, 35 and 38 are opened by the spring 36 and a second brake application results. In this manner, the progress of the train is successively restricted 80 when the steam is cut off and the governor driving mechanism is disconnected, so that a train may not proceed without restriction under these conditions. If it is found desirable to decrease the time interval during which 85 the electro-pneumatic valve EPV is maintained energized, the valve 28 may be provided with suitable leak ports which will permit the air pressure which is trapped in the chamber 30 by the check valve 44, to leak 90 away more rapidly, thus causing more frequent successive brake applications.

Considering now a train equipped with a control system embodying the modification shown in Fig. 2, assume that such train comes 95 to a stop under clear, caution or danger traffic conditions, and with the governor driving mechanism in its proper operating condition. As the train approaches a stop, the steam will be cut off and the brakes, including the brakes 100 on the engine and tender, will be applied, thus causing the valve 28 of the device D to be moved to the right, admitting air pressure from the brake cylinder pipe to the chamber 30, and so closing the contacts 37, 35 and 38. 105 An automatic brake application as a result of the zero speed condition of the centrifuge G will thus be avoided by the energization of the electro-pneumatic valve EPV through the contacts 37, 35 and 38, and a circuit which has 110 been traced above. If the engine and tender brakes remain applied until the train is about to start, the air pressure in the chamber 30 will be maintained, and when the brakes are released to start the train, the check valve 44 115 will trap this air pressure until the train is in motion and the speed arm 20 is in engagement with the contact segment 24, thus maintaining the electro-pneumatic valve EPV energized and avoiding an automatic brake 120 application. If, however, the engine and tender brakes have been released while the train is at a stop and the train remains stationary for some time, the air pressure trapped in the chamber 30 may be reduced 125 by leakage to such an extent that the contacts 37, 35 and 38 are opened, the electro-pneumatic valve EPV de-energized and an automatic brake application is effected. As a result of this automatic brake application, the 130

air chamber 30 is recharged from the "brake cylinder pipe" closing the contacts 37, 35 and 38, and permitting the release of the brakes. In this manner, the train may be released 5 from an automatic brake application while at a stop. If desired, the valves or leak ports of the air chamber 30 may be designed to retain this chamber charged and the contacts 37, 35 and 38 closed for a period of time long 10 enough to permit the train to make an ordinary stop.

From the description of the device embodying the present invention it is seen that a system has been provided whereby an automatic brake application is imposed if the 15 driving mechanism for the car-carried equipment becomes inoperative while the train is in motion regardless of traffic conditions ahead, and further, that this system will not cause an automatic brake application if the 20 centrifuge or other speed responsive device has come to its zero speed position because of lack of motion of the train.

As the governor drive checking device comprising the present invention has been described in a rather specific manner and in connection with one specific type of train control system, it should be clearly understood that this device may be modified or combined with 30 other equipment, and further that this device could be employed with any suitable type of speed control system without departing from the spirit of the present invention as defined by the appended claims.

35 What it is desired to secure by Letters Patent is:—

1. In an automatic train control system, in combination with a steam propelled vehicle vehicle carried apparatus comprising a speed 40 responsive device driven in accordance with the movement of the vehicle, a brake control device controlled by said speed responsive device in accordance with influences corresponding to traffic conditions ahead, and 45 means for causing an automatic brake application if said speed responsive device indicates a zero speed for more than a limited period of time while steam is supplied to propel the vehicle.

50 2. In an automatic train control system, in combination with a steam propelled vehicle, vehicle carried brake control apparatus including a speed responsive device driven in accordance with the progress of the vehicle, 55 a control means cooperating with said speed responsive device for applying the brakes of the vehicle in response to influences corresponding to unfavorable traffic conditions ahead, means for applying the brakes of the 60 vehicle when said speed responsive device registers a zero speed, and means for preventing said last mentioned brake application when no steam is supplied to propel the vehicle and for a limited time interval after 65 steam is so applied.

3. In an automatic train control system, in combination with a vehicle having a steam boiler and a steam engine, vehicle carried control apparatus comprising a speed responsive device driven in accordance with the motion of the vehicle, a brake applying device controlled by said speed responsive device in accordance with influences inductively received from the trackway and corresponding with traffic conditions ahead, and 70 additional means for actuating said brake applying device if said speed responsive device fails to indicate a motion of the vehicle while steam is being supplied to said engine from said steam boiler. 75

4. In an automatic train control system, a brake applying device adapted to apply the brakes of a vehicle when de-energized, means for controlling said brake applying device including a control device operated in accordance with influences corresponding to traffic conditions ahead and a speed responsive device driven in accordance with the motion of the vehicle, means for de-energizing 80 said brake applying device when said speed responsive device indicates a zero speed and means for preventing the de-energization of said brake applying device while steam is cut off from the propelling mechanism of the vehicle and for a limited interval of time after 85 steam is admitted to said propelling mechanism. 90

5. In an automatic train control system, a brake applying device adapted to apply the brakes of a vehicle when de-energized, means for controlling the energization of said brake applying device in accordance with influences corresponding to traffic conditions ahead and in accordance with the vehicle speed, said means including a speed responsive device 100 driven in accordance with the motion of the vehicle and adapted to de-energize the brake applying device when in its zero speed position, and a switch for maintaining said brake applying device energized as long as steam 105 is not applied to the vehicle propelling mechanism and for a limited time interval after steam has been so applied, said switch being operated by fluid pressure. 110

6. In an automatic train control system, a steam propelled vehicle, vehicle carried brake control apparatus including means driven in accordance with the motion of the vehicle and acting to control the vehicle brakes, said brake control apparatus acting to apply the brakes of the vehicle when said driven means fails to operate, and means for preventing said brake application when no steam is supplied to the vehicle driving mechanism and a brake application has already been initiated. 120

7. In an automatic train control system for steam propelled vehicles, the combination with a centrifugal speed-responsive device driven from the car wheels, of means initially operated automatically after an interval of 125 130

delay when steam is supplied to propel the vehicle and maintained in its operated condition so long as steam is supplied, and means for automatically applying the brakes of the vehicle upon operation of said means if said speed responsive device is not rotating.

8. In an automatic train control system for steam propelled vehicles, in combination, a normally energized electro-pneumatic valve 10 acting automatically upon de-energization thereof to cause a brake application, a normally closed energizing circuit for said valve including two branches in multiple, a speed responsive device controlling one multiple branch to open it when said device is not rotating, and other contacts in the other multiple branch initially opened after an interval of delay when steam is supplied to propel the vehicle and maintained open so 20 long as steam is supplied.

9. In an automatic train control system for steam propelled vehicles, means for determining, by restricting the vehicle, when the vehicle is in motion including, a circuit controller, and pressure responsive means for operating said circuit controller to open its circuit when steam is supplied to propel the vehicle and thus restrict the vehicle a short time after said steam is supplied, if the vehicle, at such time, be motionless.

10. In an arrangement of the character described for detecting failure of devices driven from car wheels, means for determining when the car is in motion including, a circuit, and means set into operation upon application of power to propel the car for opening said circuit if the device driven from the car wheels is not operating after an interval of delay.

40 11. In an automatic train control system, the combination with a speed-responsive device driven from the wheels of the vehicle, a control device arranged to become effective only after a predetermined lapse of time after vehicle propulsion power has been turned on, and means for automatically applying the brakes of the vehicle when said control device is effective and said speed-responsive device is not rotating.

50 12. In an automatic train control system, car-carried apparatus comprising a normally energized electro-pneumatic valve, acting automatically upon de-energization thereof to cause a brake application, an energizing circuit for said valve including two branches in multiple, a speed responsive device driven from the car wheels and operating contacts in one of said multiple circuits, said contacts being opened when said speed responsive device is not in motion, and means maintaining contacts in said other multiple circuits closed when the vehicle brakes are applied, and for a predetermined time interval after said brakes are released.

65 13. In an automatic train control system,

vehicle carried apparatus comprising a speed responsive device driven from the wheels of the vehicle, a brake control device, controlled by said speed responsive device in accordance with influences corresponding to traffic conditions ahead, means for actuating said brake control device when said speed responsive device is not in motion, and means for preventing such brake application if a brake application is already in effect, and for a predetermined time interval after the release of said brake application.

70 14. In an automatic train control system, a speed responsive device driven in accordance with the progress of a vehicle, a control device operating after a predetermined interval of delay after the release of the vehicle brakes, and means for automatically applying the vehicle brakes if said control device is operated and said speed responsive device indicates a zero speed.

80 15. In an automatic train control system, an automatic brake applying means, a rotary speed responsive device driven from the wheels of the vehicle, means operated by said speed responsive device for causing an automatic brake application when said speed responsive device is not rotating, a control device effective when the vehicle brakes are applied and for an interval after said brakes are released, said control device acting when effective to prevent said automatic brake application.

90 16. In an automatic train control system, a device driven from the car wheels and means for detecting a failure in the driving mechanism of said device comprising a normally closed circuit opening when said device is not in operation, a second circuit, contacts for controlling said second circuit when said device is not in operation and means for closing said contacts comprising a cylinder containing a flexible diaphragm connected to said contacts, and means for admitting air pressure to said cylinder to close said contacts when the power for propelling the vehicle is cut off and for a predetermined time interval after such power is applied.

100 17. In an automatic train control system, a device driven from the car wheels and means for detecting a failure in the driving mechanism of said device comprising a normally closed circuit opening when said device is not in operation, a second circuit, contacts for controlling said second circuit when said device is not in operation and means for closing said contacts comprising a cylinder containing a flexible diaphragm connected to said contacts, and means for admitting air pressure to said cylinder to close said contacts when the power for propelling the vehicle is cut off and the vehicle brakes are applied, said means acting to maintain said air pressure to maintain said contacts closed for a predetermined time interval after the power

is applied and after the brakes are released.

18. In an automatic train control system, a device driven from the car wheels and means for detecting a failure in the driving mechanism of said device comprising a brake applying device, means for operating said brake applying device when said driven device is not in operation and means for preventing such operation of said brake applying device unless power is being applied to propel the vehicle.

19. In an automatic train control system, in combination with a steam propelled vehicle, vehicle carried brake control apparatus including a speed responsive device driven in accordance with the progress of the vehicle, a control means cooperating with said speed responsive device for applying the brakes of the vehicle in response to influences corresponding to unfavorable traffic conditions ahead, means for applying the brakes of the vehicle when said speed responsive device registers a zero speed, and

retarded action fluid pressure operated means for preventing said last mentioned brake application when no steam is supplied to propel the vehicle.

20. In an automatic train control system, a brake applying device for applying the brakes of a vehicle, means for controlling said brake applying device including a control device operated in accordance with the influences corresponding to traffic conditions ahead and a speed responsive device driven in accordance with the motion of the vehicle, means for causing said brake applying device to apply the brakes when said speed responsive device indicates zero speed, and means for preventing such application of said brakes during the time that steam is cut off from the propelling mechanism of the vehicle and for a limited interval of time if steam is admitted to said propelling mechanism.

In testimony whereof I affix my signature.
HERBERT B. TAYLOR.
